UNITED STATES PATENT OFFICE.

BERT W. HALLSTEAD, OF SCRANTON, PENNSYLVANIA.

SPARK-PLUG.

No. 818,872.

Specification of Letters Patent.

Patented April 17, 1906.

Application filed November 5, 1904. Serial No. 231,580.

To all whom it may concern:

Be it known that I, BERT W. HALLSTEAD, a citizen of the United States, residing at Scranton, in the county of Lackawanna and 5 State of Pennsylvania, have invented certain new and useful Improvements in Spark-Plugs; and I do hereby declare the following to be a full, clear, and exact description of the invention, such as will enable others skilled 10 in the art to which it appertains to make and use the same.

This invention relates to improvements in 15 sparking apparatus for explosive - engines, and more particularly to a sparking plug provided with means for preventing loss of current by short-circuiting or by the jumping of spaces at points other than within the explosive-engine.

With this and further objects in view the 20 invention comprises certain novel constructions, combinations, and arrangements of parts, as will be hereinafter fully described and claimed.

In the accompanying drawings, Figure 1 25 represents a view in side elevation of a spark-plug embodying the features of the present invention. Fig. 2 represents a longitudinal vertical central section taken therethrough.

In the igniting of explosive charges with- 30 in the cylinders of gas-engines it has been a difficult matter to effectually control the currents of electricity supplied for producing sparks, such currents being necessarily of high potential and readily leaking or straying 35 wherever insufficient insulation occurs or jumping any short spaces, and in order to avoid this waste of current and insure the sparking being produced within the cylinder of the explosive-engine, as well as to at- 40tain other valuable results, I employ a structure such as is disclosed in the accompanying drawings, in which—

1 represents the casing or body portion of the plug, which is formed with a reduced 45 threaded shank 2, the enlarged portion of the plug being provided with a polysided outer surface 3, adapted to be engaged by a wrench for threading the shank 2 into the aperture provided therefor in the cylinder of the en- 50 gine. The shank 2 of the plug is bored longitudinally, and a conductor 4 extends centrally throughout the length thereof, as well as through the enlarged body portion, and at its inner or sparking end is preferably provided 55 with a tip of platinum, as at 5. Of course the use of platinum is arbitrary; but in prac-

tice the same serves to prevent destruction of the conductor. The shank 2 is internally threaded at its inner end, as at 7, and a cap 8 is threaded into said shank, a ring 9 being ar- 60 ranged within the shank 2 and a similar ring 10 being arranged at the inner end of the threaded portion of the cap 8, the space between the rings 9 and 10 being filled by mica or other suitable insulating disks 11, through 65 which the conductor or stem 4 extends, said conductor being supported by said disks and maintained at a suitable space from the shank 2. The cap 8 is made up of a hollow body portion which is threaded, as above men- 70 tioned, into the end of the shank 2 and a cover 12 carried at the outer end of said body portion. The cover 12 is apertured centrally, through which aperture projects the inner end of the stem 4, and said aperture is lined 75 by a ring 13, preferably of platinum or other suitable material.

The stem or conductor 4 is threaded intermediate its length, as at 14, and engaging said threaded portion are sleeve-nuts 15 15, 80 facing in opposite directions and having their sleeves either in contact or directed toward each other. The inner sleeve-nut 15 is ar- ranged to engage mica or other suitable disks 16, surrounding the stem 4 and filling the 85 space between the said nut and the annular shoulder 17, connecting the shank 2 with the main body portion of the plug 1. The outer end of the main body portion of the plug 1 is internally threaded, and a cap 18 is threaded 90 into the same and is apertured centrally, as at 19, through which aperture extends the stem 4, mica or other suitable insulating-disks 20 surrounding the stem 4 and being disposed between the outer nut 15 and the cap 18. 95

It will be observed that the nuts 15 serve to retain the stem 4 against longitudinal movement and that the mica disks 11, 16, and 20 retain the same against lateral movement and support the same spaced from the sur- 100 rounding casing at all points.

The stem 4, while normally maintained, as above stated, against longitudinal and lateral movement, is capable of longitudinal adjustment by being threaded in either di- 105 rection within the nuts 15, so that the tip 5 may be adjusted to a nicety with respect to the ring 13. The nuts 15 may be spread apart to any degree required for causing the opposite ends to engage the mica 16 and 20, 110 respectively, when the cap 18 is threaded home, so that such mica will be compressed

and the parts will be firmly held in place, the space between the stem 4 at any point intermediate the length thereof and the inclosing casing being sufficiently great to constitute a good insulator for high-potential currents, especially as the atmosphere within the plug will, due to the heat of the engine operated, be maintained in a dry condition. Thus it will be observed that the air-gap between the stem and the surrounding parts of opposite polarity is depended upon for preventing leakage, and the danger of short-circuiting prevalent with ordinary insulators from defects in such insulators is largely obviated.

In practice the shank 2 is threaded through the wall of the cylinder of an engine until the inner end of said shank projects within the engine, so that the spark produced between the tip 5 and the ring 13 will readily ignite the charge within the engine, and the chamber formed in the cap 8 in the rear of the ring 13 permits of the ready circulation of gases between the tip 5 and the ring 13, suitable discharge-openings 21 being formed in the wall of the cap 8 for permitting the discharge of gases entering the chamber within the cap 8. The circulation of the gases about the tip 5 and within the chamber formed within the cap 8 will tend to cool the said tip and the ring 13 and prevent excessive heating of the stem 4. In the operation of a gas-engine when the charge of explosive gas has been compressed within the cylinder the gases will of course fill the chamber formed within the casing 8, and as soon as the compressing-stroke of the piston of the engine is completed the circuit including the stem 4 and the plug 1 will be closed by any ordinary make-and-break device, whereupon the resistance occasioned by the air-gap between the tip 5 and the ring 13 will be overcome, due to the high voltage of the current, and a spark will be produced between said tip and ring which will ignite the gases surrounding said tip and explode the charge within the cylinder.

Each of the nuts 15 is made of a material which expands under the action of heat more readily than does the material from which the cap 18 and the plug 1 is formed. The cap 8 is made of a similar material to the nuts 15, so that during operation when the parts become heated the expansion of the material forming plug 1 and cap 18 will not produce loosening of the insulating-disks 11, 16, and 21; but as the cap 8 and nuts 15 expand at a greater rate than the plug 1 and cap 18 the disks 11, 16, and 21 will be compressed and held firmly in place. While I do not limit my invention to any particular materials, for illustration I would suggest that the nuts 15 and the cap 8 might be made of brass, while the plug 1 and cap 18 might be made of steel and the object above suggested attained. Of

course any other metals which are practical for the purpose might be used, so long as the relative ratio of expansion and contraction is maintained.

Having thus fully described my invention, what I claim as new, and desire to secure by Letters Patent, is—

1. A spark-plug comprising a body portion, a cap carried by said body portion, a conductor-stem extending longitudinally through said cap and body portion, a body of insulating material surrounding said stem and engaging the walls of said body portion, for spacing the stem from said body portion a similar body of insulating material surrounding the stem and engaging the cap for spacing the stem from the cap, and means carried by the stem and interposed between said bodies of insulating material for spreading said bodies apart and pressing the same against said body portion and cap respectively.

2. A spark-plug comprising a body portion, a conductor-stem extending longitudinally through the same, separate bodies of insulating material surrounding said stem and engaging the walls of said body portion for spacing the stem from the body portion, and a plurality of nuts interposed between said bodies of insulating material for spreading said bodies apart and pressing the same against said body portion and cap respectively.

3. A spark-plug comprising a hollow body portion, a stem extending through the same, insulating material engaging the walls of said body portion and supporting said stem out of contact therewith, part of said insulating material being spaced from another part thereof, a nut threaded onto said stem between said parts of insulating material and engaging one part thereof, and a second nut also threaded onto said stem between said parts of insulating material and engaging the other part thereof.

4. A spark-plug comprising a hollow body portion, a stem extending longitudinally, centrally therethrough, disks of insulating material surrounding said stem and engaging the walls of said body portion for spacing the stem therefrom, and a pair of sleeve-nuts threaded onto said stem between the disks of insulating material and engaging said disks for retaining the stem against longitudinal movement.

5. A spark-plug comprising a body portion, a conductor-stem extending longitudinally through the same, separate bodies of insulating material surrounding said stem for spacing the same from the body portion, means spaced apart and carried by said stem and interposed between said bodies of insulating material for maintaining the same in position, and means for retaining said interposed means against movement longitudinally of said stem.

6. A spark-plug comprising a body portion, a conductor-stem extending through the same, insulating-disks arranged within said body portion and supporting said stems and nuts carried by said stem and engaging said insulating material for retaining the same in position, said nuts being formed of a material capable of expanding under the ac-

tion of heat at a greater rate than the body portion.

In testimony whereof I affix my signature in presence of two witnesses.
